UNITED STATES PATENT OFFICE.

GEORGE R. GILLETTE, OF MEDFORD, MASSACHUSETTS, ASSIGNOR TO ELLIOTT AD-
DRESSING MACHINE COMPANY, OF CAMBRIDGE, MASSACHUSETTS, A CORPORATION
OF MAINE.

STENCIL-PRINTING DEVICE.

Application filed May 6, 1924. Serial No. 711,496.

This invention relates to printing wherein the characters to be printed are carried by stencils, and especially by stencils having a relatively flexible ink-retaining sheet.

5 In certain classes of work as, for instance, the printing of time cards, pay roll sheets, or the addressing of letters and envelopes, and the like, it is desirable for one purpose to print the entire characters carried by the stencils and for another purpose to print 10 only selected characters carried by the stencils.

An object of this invention is the provision of means whereby a predetermined 15 portion of the stencil may be shielded from the action of the printing device so that the characters located in the unshielded portions of the stencils only shall be used for printing.

20 A further object of the invention is the provision of means to prevent the application of pressure to the shielded portion of the stencil during the printing operation.

A further object of the invention is generally to improve the construction and operation of stencil printing machines and processes.

25 Fig. 1 is a perspective view, partly diagrammatic, of the essential elements of a stencil printing machine employed in conjunction with the invention.

30 Fig. 2 is a sectional view taken along line 2—2 of Fig. 1 and illustrating the stencil shutter embodying the invention in position 35 to shield a portion of the printing area of the stencil.

35 Fig. 3 is a view similar to Fig. 2 and illustrating the manner in which the shutter acts to shield a portion of the stencil and 40 support it against the pressure-action of the printing roller and platen.

45 Fig. 4 is a plan view of a stencil which may be associated with the invention; and further illustrating in dotted lines the position 50 of the stencil shutter to shield a portion of the printing area of the stencil.

55 Fig. 5 is a perspective view of the obverse face of the stencil shutter embodying the invention.

50 Fig. 6 is a view similar to Fig. 5 but illustrating the reverse face of the stencil shutter.

55 Fig. 7 is a detail of a portion of Fig. 1 showing a guide for holding the shutter above the track.

60 As shown in Fig. 1, the stencil printing machine with which this invention may well be associated includes the two parallel tracks 10 and 11 which are formed or provided with stencil-receiving grooves or race-ways 12 in their proximate faces. Stencils are adapted to be contained loosely in said grooves 12 and moved therealong into a printing position beneath an ink roll 14 or other printing device for printing, in which 65 position the stencils are held motionless, momentarily. The ink roll may be supported for a vertical movement by suitable means as the arms 15 between and by which the roll may be rotatably supported, and said roll is adapted to be moved downwardly and into pressure contact with the stencil disposed therebeneath, whereby to force ink 70 through the printing characters carried by the stencil and record the characters on a work sheet *a*, which sheet may be supported on a table or bed 16 disposed beneath the stencil track. At the same time the printing device is moved downwardly into contact 75 with the stencil, an anvil 17 may be moved upwardly through an opening in the table 16 whereby to move the sheet *a* upwardly into contact with the lower face of the stencil.

80 A pile of superimposed stencils may be contained in a stencil receiver 18 disposed at one end of and in communication with the tracks 10 and 11 and suitable stencil delivery mechanism which may include a pusher 19, may serve to deliver the lowermost stencils successively from the stencil holder into and move them along the tracks 10 and 11. A stencil receiver 20 may be disposed at the opposite end of said tracks 10 and 11 in position to receive the used stencils.

85 The stencil with which this invention is particularly related, although not limited, may have a border or frame 24 of relatively stiff material, as cardboard. A sheet of sten-

cil paper 25 may be secured to and disposed within the border of said frame. It is a characteristic of the stencil herein illustrated, and with which this invention is 5 particularly concerned, that the stencil sheet 25 is coated with a layer of hardened gelatine or the like, which layer is adapted to be cut or displaced, in the act of impressing the printing characters on the sheet, thereby 10 to expose the body of the sheet to be penetrated by the ink contained on the ink roll, when the ink roll is brought into pressure-contact with the stencil; and the sheet subsequently may retain ink in the printing characters. The stencil sheet is relatively yielding under the printing pressure, also.

Ordinarily there is sufficient room on the stencil sheet 25 to accommodate a number of horizontal lines of characters and with the 20 stencil shown in Fig. 4 there is sufficient space to accommodate four lines of characters, the numerals "555" in the illustration occupying two of the four lines available.

In the ordinary operation of the stencil printing machine, the printing device, as the 25 ink roll 14 is adapted to engage with substantially the entire area of the stencil sheet 25. For many purposes, it is desirable, at times, to shield certain of the characters 30 against the action of the printing device whereby to prevent pressure from being applied to that portion of the stencil sheet containing the undesired characters and thereby preventing the printing of the undesired 35 characters. Accordingly it is an object of this invention to provide a shield or shutter which can be interposed between the stencil and the printing device and cover the undesired portion of the stencil and also support such 40 portion against the printing pressure of the printing device, and also of the anvil. The shutter may comprise a plate 30 formed, preferably, of sheet metal, which plate may be of any suitable shape but preferably is 45 about as long and as wide as the stencil. The plate is preferably rigid and unyielding whereby to withstand the printing pressure of the printing device without being deflect- 50 ed into pressure contact with the stencil sheet 25 of the stencil.

The shutter is provided with a lower stencil-engaging face 31 adapted to overlie that portion of the stencil containing the characters to be printed, and a relieved portion or recess 32 connected by a lip 33 with the stencil-engaging face. Said relieved portion or recess is adapted to overlie that 55 portion of the stencil containing the undesired characters. The stencil-engaging face 60 31 is formed with an aperture 34 therethrough which is adapted to expose the desired stencil characters for access by the printing roll, which roll is adapted to be deformed, under the printing pressure, and 65 enter said slot and bear against the exposed

portion of the stencil. Said slot may have its opposite side edges 34a beveled, as shown, to facilitate the engagement of the printing roll with the stencil. As here shown, the shutter is arranged to cover or shield the 70 upper two lines of the stencil and expose only the lowermost characters for printing.

The stencil printing machine is provided with means to hold the shutter removably in position above and on the stencil tracks 75 and under the printing roll. Said means may include the guides 35 carried by said tracks, and said guides are or may be shaped and arranged to engage the opposite corners of the shutter and hold it removably in position on the track.

During the printing operation, the printing roll and the anvil move together at the same time and the anvil raises the sheet *a* 80 upwardly and against the lower face of the 85 stencil and holds it in such position while the printing roll engages the upper face of the stencil and forces ink through the stencil onto the sheet. The ink roll is deformed as is illustrated in Fig. 3 and a portion 90 thereof enters the slot in the shutter and thereby causes the exposed characters borne by the stencil to be printed. The blank portion of the shutter shields the undesired portion of the stencil against pressure contact with the roll. The anvil is adapted to be relatively unyielding and consequently that portion of the stencil disposed under the relieved portion or recess 32 of the shutter is free from pressure engagement with 95 the sheet *a* and consequently, even though the characters located in this portion of the stencil may bear ink deposited therein from a previous printing operation, these characters will not be recorded on the sheet. 100

I claim:

1. In a stencil printing machine, inking means arranged normally to bring the stencil and the work into pressure-engagement for printing, and rigid means interposed between the inking means and the stencil to shield a portion of the stencil against pressure-engagement with the work. 110

2. In a stencil printing machine, a yielding printing device and an anvil cooperating 115 to bring the stencil and the work into pressure-engagement for printing, and rigid means interposed between the printing device and the stencil to shield a portion of the stencil against and expose a portion thereof for pressure-engagement with the work. 120

3. In a stencil printing machine, a yielding device arranged to engage the flexible stencil, an inflexible anvil cooperating with 125 said inking device to bring the stencil and the work into pressure-engagement for printing, and rigid means to shield a portion of the stencil against such pressure-engagement and expose a portion thereof for 130

such pressure-engagement and contact with said inking device.

4. In a stencil printing machine operating on flexible stencils, a printing device arranged to be moved into pressure-contact with the flexible stencil, and rigid means interposed between the printing device and the stencil to shield a portion of the stencil against and expose a portion thereof for such pressure-contact.

5. In a stencil printing machine, a yielding printing device arranged for pressure-contact with the stencil, and a relatively stiff and unyielding plate interposed between the printing device and the stencil and arranged to be engaged by said printing device and support a portion of the stencil against pressure-contact with said device, said plate having an aperture therethrough which exposes a portion of the stencil for contact with said printing device.

6. In a stencil printing machine, an anvil, a superposed yielding printing device adapted for pressure-engagement with a stencil overlying said anvil, and a relatively stiff and unyielding plate adapted to overlie the stencil and support a portion of said printing device against pressure-contact with the stencil, said plate having an aperture therethrough the access of another portion of said printing device with said stencil, the lower face of said plate having a relieved portion adjacent said aperture.

7. In a stencil machine, a stencil track adapted to support the opposite marginal portions of the stencil, an inking device movable into pressure-engagement with the stencil, and removable and relatively rigid means disposed between the stencil track and said inking device, and constructed and arranged to shield a portion of the stencil against the pressure action of the printing device.

8. In a stencil printing machine, a stencil track adapted to support the opposite marginal portions of the stencil, an inking device movable into engagement with the stencil, and removable means disposed between the stencil track and printing device and constructed and arranged to shield a portion of the stencil against the action of the printing device, said means including a relatively inflexible plate adapted to cover a portion of the stencil and shield it against the pressure of said inking device and having an aperture adapted to expose a portion of the stencil to the action of said inking device.

9. In a stencil printing device, a stencil track adapted to support the opposite marginal portions of the stencil, an inking device disposed above, and an anvil disposed below, the stencil in the track and cooperating with said inking device to press the stencil into contact with the work, and

rigid means having a removable support upon said track and above the stencils and arranged to shield a portion of the stencil against and expose a portion to the pressure action of said inking device and anvil. 70

10. In a stencil printing device, a stencil track adapted to support the opposite marginal portions of the stencil, a deformable inking device disposed above and an anvil disposed below the stencil on the track and cooperating with said inking device to press the stencil into contact with the work, and means to shield a portion of the stencil against and expose a portion to the pressure action of said inking device and anvil comprising a relatively inflexible plate carried by the stencil track below said deformable inking device and above the stencil, said plate having an apertured portion adapted to expose a portion of the stencil, and an adjacent solid portion adapted to shield the remainder of the stencil, and said deformable inking device arranged to have a portion thereof bear against the solid portion of the plate and yield and deform to permit another portion thereof to enter the aperture in the plate and bear against the exposed portion of the stencil. 80

11. A stencil printing machine having an anvil adapted to support the work, a deformable inking device adapted to engage a stencil superposed over the work and press it into contact with the work, and a relatively inflexible plate superposed over the stencil and under the inking device, said plate having a solid portion overlying a portion of the stencil, and an apertured portion overlying another portion of the stencil, and a relieved portion in the lower face of the solid portion. 95

12. A stencil shutter adapted to overlie a stencil and shield a portion thereof against printing, said shutter comprising a relatively unyielding plate having an aperture arranged to expose a portion of the stencil for printing, and having a relieved portion adapted to overlie the shielded portion of the stencil. 100

13. A stencil shutter adapted to overlie a stencil and shield a portion thereof against printing, said shutter comprising a relatively unyielding plate having a stencil-engaging face formed with an aperture through which a portion of the stencil may be exposed for printing, and a relieved portion adjacent the stencil-engaging face which is adapted to overlie the shielded portion of the stencil. 115

14. A stencil shutter comprising a relatively inflexible plate having a lower stencil-engaging face and a relieved portion adjacent said stencil-engaging face, and a slot extended through said plate and lying within the borders of said stencil-engaging face. 120

15. A stencil shutter comprising a rela- 130

tively inflexible plate having approximately the dimensions of the stencil with which it cooperates, said plate having a lower stencil-engaging face which occupies the long dimension of the plate, and a slot extended through said plate in the long dimension thereof and within the border of said sten-

cil-engaging face, and said plate having a relieved portion adjacent said stencil-engaging face and in the long dimension of said plate. 10

In testimony whereof, I have signed my name to this specification.

GEORGE R. GILLETTE.
